United States Patent Office.

PATRICK HANLY, OF NEW YORK, N. Y.

Letters Patent No. 72,485, dated December 24, 1867.

IMPROVEMENT IN HORSE-SHOES.

The Schedule referred to in these Letters Patent and making part of the same.

TO ALL WHOM IT MAY CONCERN:

Be it known that I, PATRICK HANLY, of the city, county, and State of New York, have invented a new and useful Improvement in Removable Cogs for Horse-Shoes; and do hereby declare that the following is a full, clear, and exact description thereof, reference being had to the accompanying drawings, making part of this specification, in which—

Figure 1 is a front view of a horse-shoe with my invention applied to it.

Figure 2, an inner or opposite side view of same.

Figure 3 is an edge view.

Figure 4, a longitudinal section.

Figures 5 and 6, transverse sections looking towards toe and heel; and

Figure 7 a rear-end elevation.

This invention relates to a novel device for temporarily roughing the shoes of a horse, for travelling on slippery ground or ice, without removing the shoes from the horse's hoofs; and consists in the application of metallic plates, containing cogs, to the face of the worn horse-shoe, by means of screws, enabling thereby an ordinary stable-hand to attach and remove the same from the worn horse-shoes in a very short space of time, whereby a saving of much labor and expense is obtained.

In the drawings, A represents a horse-shoe, with my invention applied to it, of which B is the toe-plate, with its cogs C C. D is a check-piece, connected with the plate B by means of screws e e, which pass through both, confining the shoe between them, and firmly securing the cogged toe-plate on the face of the shoe. G is the heel-plate, having cogs H H on its face. This cogged heel-plate is fastened on the shoe by means of lips I I, which lean over on the inside or bevelled edge α of the shoe, (see figs. 2 and 6,) and set-screws K K, which pass through the lips I I.

The heads of the set-screws K K abut against the heel of the shoe, (see fig. 1,) and, drawing the heel-plate toward the heel of the shoe, secure the same firmly in place. These plates may be used separately or together, as circumstances require; and, to prevent balling of the hoofs of the horse by snow or dirt, I place a sheet of India rubber, L, or other elastic substance, on the frog of the hoof, and between the shoe and the heel and toe-plates.

From the above it will be seen that I have produced a very convenient and inexpensive device, which can be easily attached to or removed from the shoes of a horse, which will effectually prevent slipping on smooth or icy ground.

Having described my invention, what I claim, and desire to secure by Letters Patent, is—

The bevel α in the horse-shoe, the plates B G, and their connections, substantially as and for the purposes described and set forth.

In testimony whereof, I have hereunto set my signature, this seventh day of November, A. D. 1867.

PATRICK HANLY.
